UNITED STATES PATENT OFFICE.

NELSON E. FUNK, OF MONTCLAIR, NEW JERSEY.

CUTTING AND SCORING UNIT FOR ROTARY PRESSES.

Application filed January 31, 1925. Serial No. 6,127.

This invention relates to cutting and scoring presses.

An object of the invention is to provide a press with cutting and scoring unit providing for variations of outline of cutting and scoring as may be desired. My invention is particularly applicable to cutting and scoring units of the cylindrical or other arcuate shape and coacting with a correspondingly shaped impression cylinder for use in a rotary press.

Pursuant to my invention, the shell of wood or other suitable material is severed along the outlines of cutting and scoring by cutting or scoring rules respectively disposed between and held at the lines of severing of the shell. The shell is preferably built up of partial cylindrical or other arcuate portions and locked with the cutting and scoring rules to a turtle or other suitable removable support on the cutting and scoring cylinder roll.

The built-up assembly is arranged for all shapes or lengths of blanks cut from the web by the use of removable turtles of varying outer diameters, the inner diameters being substantially uniform and conforming to the outer diameter of the cutting and scoring cylinder roll.

Further features and objects of the invention will be more fully understood from the following detail description and the accompanying drawings, in which

Fig. 1 is a perspective view of a rotary press including the usual printing or color impression rolls, and provided with a cutting and scoring unit embodying my invention; this figure shows the press as a whole as viewed from its feeding end;

Fig. 2 is a perspective view of the press shown in Fig. 1, but as viewed from its delivery end;

Fig. 3 is a perspective view of an end portion of my cutting and scoring unit assembled with the impression cylinder, on a somewhat larger scale; this figure illustrates a printed web cut and scored by my cutting and scoring unit;

Fig. 4 is a sectional elevation on line 4—4 of Fig. 3;

Fig. 5 is a detail view and Fig. 6 a perspective view of one end portion of the cutting and scoring roll, the turtle and the cutting and scoring unit; and

Fig. 7 is a perspective view of one form

of appliance for forming my cutting and scoring roll.

It will be understood that my invention is applicable to cutting and scoring units for use with any desired types of printing or color presses, and that the invention is not limited to the particular type of printing or color press illustrated in Figs. 1 and 2.

In Figs. 1 and 2, I have shown a printing press of the desired number of color impression rolls, and comprising generally the base 10 having oppositely disposed standards 11, 11 in which is journaled the shaft 12, carrying the roll cylinder 13 for supporting the roll 14 of paper. The web 15 of the roll 14 is passed to the printing unit 16 which includes the desired number of printing or coloring rolls as indicated. The printed web is indicated at 17.

The cutting and scoring unit embodies the oppositely disposed standards 18, 19, in which is journaled the cutting and scoring cylinder 20 and the impression cylinder 21, see also Figs. 3 and 4. The cutting and scoring shell 22 is provided with a suitable support 23, which is removable from the cutting and scoring cylinder 20. Preferably, the cutting and scoring cylinder 20 is journaled in adjustable bearings 24, 24, respectively in the opposite standards 18, 19, as by means of bearing blocks 25 respectively adjustable in the slots 26 and set by means of the respective screw wedges 27, see Fig. 2. In a similar manner, the impression cylinder 21 is journaled at its opposite ends in the adjustable bearings 28, 28.

The printed blank 17 upon delivery from the printing unit 16 passes between the cutting and scoring shell 22 and the impression cylinder 21 and is thereby cut and scored to the desired outlines. The completed blanks 29, see Fig. 2, are delivered at the delivery end of the press to any suitable table or to the usual set of guide rolls, or equivalent.

Referring to Figs. 3 and 4, the removable support 23 of the cutting and scoring shell 22 on the cylinder 20 is in the form of what I have termed a "turtle" which is described more fully hereinafter.

The cutting and scoring shell 22 is preferably formed of composite parts or strips 30 secured by screws 31 or the like to the turtle 23. Such strips 30 extend lengthwise or axially of the cylinder 20, the length and

width of each strip 30 conform to the length and curvature of the cutting of the slots 32 in which the cutting and scoring rules are located and locked, as will appear more fully herein.

It will be observed from Fig. 3 that the group of cutting and scoring rules corresponding to each individual blank is duplicated lengthwise of the cylinder 20 and also circumferentially of the cylinder 20 for the purpose of attaining a maximum number of groups of cutting and scoring rules about the periphery of the cylinder 20 and to minimize the waste of the web. The cutting rules are provided with sharpened edges serving as knives in coaction with the impression cylinder 21, and extend from the axis of the cylinder 20 radially sufficiently to fully sever the web, whereas the scoring rules are of a construction similar to the cutting rules, but of lesser radial extension relative to the axis of the cylinder 20. In Fig. 3, the cut outline of the blank is illustrated in full outline as indicated at 33 and the scoring outline is illustrated in dash outline as indicated at 34. The printing 35 is varied, as will be understood.

A preferred method of forming the strips 30 of the cutting and scoring shell 22 is illustrated in Figs. 6 and 7, the subject matter of which forms a separate application filed by me under date of January 31st, 1925, Serial No. 6,128, bearing the title of Method and means of forming cutting and scoring units. In general, the lines of cutting of the unit 22 are substantially radial relative to the center of the turtle 23, that is, to the axis of the cylinder 20. Comparing Fig. 6 with Fig. 3, the cutting rule 36 provides for the particular line of cutting 37 of a blank 29. It will be noted that the cutting rule 36 is positioned against the face 38, see Fig. 6, of a strip 30. The cutting rule 39 provides for the particular line of cutting 40 in a blank 29 and is positioned against the face 41, see Fig. 6, of a particular strip 30. The locking of the cutting rules 36, 39 against the respective faces 38, 41 is attained by the short strip or block 42 having its faces 43, 44 cut radially. The block 42 is secured in position on the turtle 23 by means of screws 45 or the like passing through the perforations 46; the screws 45 are tapped within the threaded openings 47 in the turtle 23, or equivalent. The heads of the perforations 46 are preferably countersunk for the purpose of locating the heads 48 of the screws 45 substantially flush with or below the upper surface of its strip 30. In a similar manner, I have indicated in Fig. 6, the cutting rules 49, 50, 51, 52, 53 and 54 which are located and locked by the block 55, and screws 45 in a corresponding manner relative to its strip 30 onto the turtle 23. The cutting rules are advantageously se-

lected of convenient lengths corresponding to the outline of cutting of the blank. As is indicated in Fig. 6, the body portion of each cutting rule is of substantial thickness; the body portions of the cutting rules are of substantially uniform thickness. The scoring rules are of similar uniform thickness but their knife edges are of lesser radial height and rounded or relatively dull. Usually the rules are selected of lengths of the respective straight-line or rectilinear portions of the outline of the blank and of the corners and of the curved portions of the outline of the blank.

As one convenient procedure of cutting the strip 30 of the cutting and scoring shell 22, I employed the device illustrated in Fig. 7 and comprising an endless band saw 60 guided and driven in the usual manner and passing through the slot 61 extending through the fixed standard 62 of the device. The standard 62 is supported at its lower end on a bench or table provided with a slot similar to the aforesaid slot 61. At the upper end of the standard 61 is mounted the base 63, rotatable horizontally. At the opposite ends of the base 63 are brackets 65 which are provided with a bearing 66 (one only being shown in Fig. 7) for respectively receiving the bearing studs 67 of the idle, supporting cylinders 68, 69. The diameter of the supporting cylinders 68, 69 corresponds to the inner diameter of the strip 30 or the outer diameter of the turtle 20. When it is desired to cut a shell strip 30, the desired outline of the blank is penciled or otherwise marked as indicated at 70 by the dash and dot marking line on the upper surface of a shell strip 30 and the cutting by the band saw 60 begun by bringing the extreme edge 71 of the marked outline 70 into engagement with the cutting edge of the band saw 60. The line of cutting at the extreme edge 71 is therefore radial, by reason of the corresponding axis of the arcuate shell strip 30 and of the supporting cylinders 68, 69. The portion 72, see Fig. 7, of the marked outline 70 is rectilinear and accordingly its cutting is attained by sliding the shell strip 30 over the supporting cylinders 68, 69 without rolling the cylinders 68, 69 and without turning the table 63. The portion 73 representing a corner in the line of cutting and of the marked outline 70 is effected by jointly rolling the shell strip 30 on the supporting cylinders 68, 69 and horizontally rotating the table 63. The portion 74 of the line of cutting is rectilinear and substantially at right angles to the aforesaid portion 72; the line of cutting along the portion 74 is attained by rolling the shell strip 30 over the supporting rolls 68, 69, in the direction of the arrow 75 while keeping the table 63 substantially quiescent. In a similar manner, the remainder of the cutting

of the marked outline 70 is carried out by similar operations.

By the provision of the adjustable bearings 24, 24 of the cutting and scoring cylinder 20 and the corresponding adjustable bearings 28 for the impression cylinder 21, each set of combined turtle 23 and cutting and scoring shell 22 of the different diameters is accommodated on the same press and the straight line travel of the printed web 17 provided for. For any cutting and scoring cylinder 20 of a given diameter, a set of turtles of varying thicknesses and uniform inner diameters are provided respectively for the made-up cutting and scoring shells 22 of varying outer diameters.

Preferably, the press is provided with suitable gearing for interconnecting the cutting and scoring unit with its impression cylinder and controlled by the hand wheel 80, see Figs. 1 and 2, for advancing or retarding the cutting and scoring cylinder 20 relative to the printing or other impression on the web for registering purposes. In a similar manner, the printing or off-set couple or couples are interconnected by gearing, controlled by the hand wheel 81 for advancing or retarding the printing or other impression lengthwise of the web for corresponding registering purposes.

From the above, it will appear that my invention provides for the assembly of cutting or scoring units or both on cylindrical or other arcuate mounting means, and affords variation of contour of cutting or scoring or both as may be desired.

Pursuant to my preferred procedure or forming the cutting and scoring unit, the body portions of the cutting and scoring knives are rules of flat stock of uniform thicknesses and the cutting and scoring edges of simple tapered formation, affording ready making up of the knives for all variations of outline of the desired cutting and scoring.

By the use of my invention, the output per unit of time is materially increased. My invention is wholly adapted to be directly attached to rotary and similar presses, and thereby attaining the desired cutting and scoring of the web as well as the printing or coloring or both by substantially a single operation.

By reason of the composite or made-up character of my cutting and scoring shell, the component strips are of relatively short

arcial lengths, thereby enabling in practice the use of strips of substantially uniform inner and outer radii of curvature respectively as well as of uniform thickness, notwithstanding that the resulting shells are 60 of different inner and outer radii of curvature.

The particular cut and scored outline of the blank illustrated in the drawings is that of a carton for a bar of soap, and it will be understood that the invention is also adapted for forming other cut and scored products such as egg boxes and the like, bearing such printed or colored impressions as may be desired.

Whereas, I have described my invention by reference to specific forms thereof, it will be understood that many changes and modifications may be made without departing from the spirit of the invention.

I claim:

1. The combination with a cylinder roll and its coupled impression roll, a set of cutting and scoring shells respectively having different inner and outer diameters and a 80 set of supports respectively for said cutting and scoring shells having substantially the same inner diameter and of different outer diameters, each of said supports being integral and of a complete circumference.

2. The combination with a cylinder roll and its coupled impression roll, of adjustable means for rotatably mounting said cylinder roll and said impression roll, a set of cutting and scoring shells respectively having different inner and outer diameters and a set of supports respectively for said cutting and scoring shells having substantially the same inner diameter and of different outer diameters, each of said supports being 90 integral and of a complete circumference.

3. The combination with a cylinder roll and its coupled impression roll, a set of cutting and scoring shells respectively having different inner and outer diameters, a set of supports respectively for said cutting and scoring shells having substantially the same inner diameter and of different outer diameters, and means for removably locking any support to the cylinder roll, each of said 100 supports being integral and of a complete circumference.

In testimony whereof I have signed this specification this 30th day of January, 1925.

NELSON E. FUNK.
